COMBINATION HEAT CUSHION AND BACK MASSAGER

Clifford E. Grube, Niles, Ill., assignor to Associated Mills,
Inc., Chicago, Ill.

Filed Jan. 16, 1967, Ser. No. 5,438

Term of patent 14 years

(Cl. D83—1)

Fig. 2

Fig. 3

Fig. 4

Fig. 5

Fig. 6

FIGURE 1 is a perspective view of a combination heat cushion and back massager employing my new design;

FIGURE 2 is a top plan view thereof;

FIGURE 3 is an elevational view of one side thereof, the other side having the same appearance;

FIGURE 4 is a bottom plan view thereof;

FIGURE 5 is an end elevation as seen from the left of FIGURE 1; and

FIGURE 6 is an end elevation as seen from the right of FIGURE 1.

I claim:

The ornamental design for a combination heat cushion and back massager, substantially as shown and described.
